METHOD OF REDUCING METAL TUBING

Sven Westin, West Allis, Wis.

Application April 6, 1939, Serial No. 266,237

13 Claims. (Cl. 205—8)

This invention relates to the art of reducing metal tubing.

Industrial demands require metal tubing of various sizes ordinarily considerably below the size at which the tubing issues from a tube forming mill. This is particularly true of seamless steel tubing regardless of the type of forming mill or forming method employed in its production.

The various tube forming mills and methods now employed are capable of producing tubing having walls of desired thickness, both as to degree and uniformity of thickness, but the problem of subsequently reducing both the external and internal diameters of the tubing to desired sizes has not been solved to best advantage.

One tube reduction method now commonly employed involves passing the formed tube in a hot condition through a multiplicity of aligned roll stands, each including a set of coating rolls forming an orifice of less size than the preceding set and driven at an exact speed higher than the rolls of the preceding set. This equipment is not only very costly, but any departure from true alignment or proper roll speed, in any of the multiplicity of stands, results in defective tubing and is the cause of much waste. Furthermore, when operated under most favorable conditions, both ends of each length of tubing, thus reduced, are always defective and end sections of substantial length must be cut off and discarded, causing further waste.

Another known method of tube reduction involves the use of a so-called draw-bench by which the tubing is drawn in a cold condition through a die. This method is time consuming and expensive, not only because it requires repeated draws through dies of different sizes, but also because it also requires annealing and pickling of the tubing before and after each draw. It is possible, however, by this draw-bench method, to reduce the tubing to sizes smaller than are obtainable by the hot rolling reduction method just described, and the primary use of the draw-bench method is, as an adjunct to the hot rolling method, in further reducing the tubing after it has been reduced as far as possible by the hot rolling method.

As heretofore practiced, the draw-bench method requires that the tubing be drawn cold. If attempted to draw hot tubing through a die, there is a tendency for the tubing to "neck" or collapse as it issues from the die, due largely to the tension involved in the drawing process.

One object of the present invention is to pro-

vide a new and more economical method of and means for reducing metal tubing.

Another object is to provide a practical method for the hot drawing of metal tubing.

Another object is to utilize a hot drawing method in the reduction of metal tubing.

Other more specific objects and advantages will appear, either expressed or implied, from the following description of a method which I have successfully employed in reducing metal tubing.

In the accompanying drawing:

Figure 1 is a longitudinal sectional view illustrating more or less diagrammatically one desirable arrangement for accomplishing the objects of this invention.

Figs. 2 and 3 are transverse sectional views taken along the lines 2—2 and 3—3, respectively, of Fig. 1.

Fig. 4 is a view of the parts shown in Fig. 1 in the relative positions occupied preliminary to starting a drawing operation.

Fig. 5 is a perspective view of a prepared tube end.

The method selected for illustration and explanation involves the use of a die 10, constituting an element of a draw-bench of a well known type, equipped with the usual draw head (not shown) adapted for gripping engagement with the leading end *a* of the tube *b*, and by which the tube is drawn through the die 10.

A bar 11 within the tube *b* makes it possible to draw the tube through the die 10 while the tube is in a highly heated condition. The bar 11 is preferably of a diameter less than the internal diameter of the reduced tube and extends into the leading end *a* of the tube, where it receives and sustains the gripping pressure of the draw-head upon the tube. The bar 11, moving with the tube *b*, passes freely through the die 10 and provides an internal brace or support for the tube, so as to limit the contraction of the tube and thus sustain the latter against "necking," as it issues from the die 10. The bar 11 also assists the tube through the die 10 by sustaining and transmitting a portion of the pulling force applied by the draw-head. The minimum clearance between the bar 11 and the die orifice 12 is preferably not less than the wall thickness of the tube *b*, so as to avoid objectionable pinching of the tube between the bar and die.

The perimeter of the die orifice 12 is considerably less than the normal perimeter of the original tube, so that a material and substantial re-

duction is effected by passing the tube through the die 10. The die orifice 12 however is preferably non-circular so as to impart a non-circular form to the tube, and the bar 11 is preferably circular, so that, as the tube issues from the die it bears against the bar along peripheral spaced zones thereon.

It will be noted, upon reference to Fig. 2, that in the particular die shown at 10 the orifice 12 thereof is of substantially oval or elliptical form, having a major horizontal axis of slightly less length than the diameter of the original tube b and a minor vertical axis of considerably less length than the diameter of the original tube, so that the tube in passing through that orifice is greatly reduced, the cross-sectional area of the reduced section c being less than half of that of the original tube b. It will also be noted that the upper and lower walls of this reduced oval section c are effectively braced against "necking" by the included bar 11, and that the arch-like formation of the sides of this oval section c is such as to render them self-sustaining.

After the tube b is reduced by passing it and the included bar 11 through the non-circular orifice 12 in the manner above described, the tube may be returned to circular form and loosened from the bar by any known or approved method. In this instance this is accomplished by passing the tube and bar through a circular orifice 13 in a second die 14. The primary function of the orifice 13 is to return the tube to true circular form, although it may also serve to effect a further slight reduction in the tube, the perimeter of the orifice 13 being substantially equal to or slightly less than that of the oval tube section c. In any event, after passing through the die 14, the resulting circular section d of the tube is entirely free from the rod 11 and may be readily withdrawn therefrom.

For convenience, the two dies 10 and 14 are preferably arranged so that the tube b and bar 11 may be passed through both on a single pass. During the pass the two dies are preferably spaced apart, as indicated in Fig. 1, so as to permit the oval section c of the tube to bear upon the bar 11 for a material distance before entering the second die 14. However, to facilitate initial entry of the tube and bar into and through the second die, and to obviate the necessity of an objectionably long point on the leading end a of the tube and bar, the second die 14 is preferably adjustable into position adjacent the die 10, as indicated in Fig. 4, in which position the pointed end a of the tube and bar may be readily projected through both dies into position to be gripped by the draw-head of the draw-bench.

During the draw stroke the die 10 is held stationary by appropriate stops 15, the die 14 traveling with and on the tube until it engages its fixed stops 16, in which position it is thereafter securely retained by the stops 16 until the tube and bar have passed through both dies.

In order to permit initial entry of the tube into and through both dies, the leading end a of the tube is pointed or otherwise reduced in any known or approved manner. In this instance the end of the tube is partially cut away, as indicated at 17 in Fig. 5, in order that it may be readily contracted about the pointed or reduced end of the bar.

Various changes may be made in the method and means hereinabove specifically described without departing from or sacrificing the advan-

tages of the invention as defined in the appended claims.

I claim:

1. The improved method of reducing tubing which comprises placing a round bar within the tubing, and pulling said bar and tubing through a non-circular die orifice having a perimeter materially less than the external perimeter of the entering tubing, the minimum clearance between said bar and the walls of said orifice being not materially less than the wall thickness of the entering tubing.

2. The improved method of reducing tubing which comprises placing a substantially round bar within the tubing, pulling the bar and tubing through a non-circular orifice having a perimeter materially less than the external perimeter of the entering tubing, the minimum clearance between the bar and walls of the orifice being not materially less than the wall thickness of the entering tubing, and pulling the bar and tubing through a substantially circular orifice to free the tubing from the bar.

3. The method of reducing tubing which consists in drawing the tube while hot through an orifice having a perimeter materially less than the perimeter of the entering tube to determine the dimensions of the tube solely by tension and external confinement, and internally bracing the tube at peripherally spaced points therein to prevent collapse thereof upon emergence from the orifice.

4. The method of reducing tubing which consists in drawing the tube while hot through an orifice having a perimeter materially less than the perimeter of the entering tube to reduce the tube without imposing tube-shaping pressure against the interior surface of the tube, and bracing the tube at peripherally spaced points therein to prevent collapse thereof upon emergence from the orifice.

5. The method of reducing tubing which consists in drawing the tube while hot through an orifice having a perimeter materially less than the perimeter of the entering tube to determine the dimensions of the tube solely by tension and external confinement, and simultaneously passing through said orifice internally of and with said tube a bar dimensioned to contact the interior of said tube at spaced peripheral points upon emergence from the orifice to thereby brace the tube against collapse.

6. The method of reducing tubing which consists in inserting a bar within the tube and drawing the tube while hot simultaneously with the bar through an orifice of a different shape than the bar and having a perimeter materially less than the perimeter of the entering tube to reduce the tube and bring the same into contact with said bar at spaced peripheral points without imposing tube-shaping pressure of the interior surface of the tube against said bar, whereby said bar braces the tube against collapse upon emergence from the orifice.

7. The method of reducing tubing which consists in inserting within said tube a bar substantially smaller than the interior of the tube, and drawing the bar and heated tube through an orifice of different shape than said bar and having a perimeter materially less than the perimeter of the entering tube, the minimum clearance between said orifice and said bar being substantially equal to the wall thickness of the entering tube whereby said bar contacts the interior of said tube at spaced peripheral points and braces said

tube against collapse upon emergence from the orifice.

8. The method of reducing tubing which consists in drawing the tube while hot through a non-circular orifice having a perimeter materially less than the perimeter of the entering tube to reduce the tube and determine the dimensions thereof solely by tension and external confinement, and simultaneously passing through said orifice with said tube and internally thereof a circular bar of a diameter equal to the maximum circle circumscribable within the reduced tube, whereby said bar contacts the interior of said tube at spaced peripheral points and braces the tube against collapse upon emergence from the orifice.

9. The method of reducing tubing which consists of drawing the tube while hot through a substantially oval orifice having a perimeter substantially less than the perimeter of the entering tube to determine the dimensions of the tube solely by tension and external confinement, and simultaneously passing through said orifice with said tube and internally thereof a circular bar having a diameter substantially equal to the smallest internal diameter of the reduced tube to thereby contact and support said tube at spaced peripheral points and brace said tube against collapse upon emergence from the orifice.

10. The method of reducing tubing which consists in inserting within said tube a circular bar of substantially smaller diameter than the interior of the tube, and drawing the heated tube and bar through a substantially oval orifice having a perimeter materially less than the perimeter of the entering tube, the minimum clearance between said orifice and said bar being substantially equal to the wall thickness of the entering tube, whereby said bar contacts the interior

of said tube at spaced peripheral points and braces said tube against collapse upon emergence from the orifice.

11. The method of reducing tubing which consists in drawing the tube while hot through a non-circular orifice having a perimeter materially less than the perimeter of the entering tube to determine the dimensions of the tube solely by tension and external confinement, internally bracing the tube against collapse upon emergence from the orifice, and passing said tube through a circular orifice to restore said tube to substantially circular shape.

12. The method of reducing tubing which consists in drawing the tube while hot through a non-circular orifice having a perimeter materially less than the perimeter of the entering tube to reduce the tube without imposing tube-shaping pressure against the interior surface thereof, bracing the tube against collapse upon emergence from the orifice, and passing the reduced tube through a circular orifice to restore its circular shape.

13. The method of reducing tubing which consists in inserting within the tube a circular bar having a diameter materially less than the internal diameter of the tube, drawing the tube while hot and the bar simultaneously through a substantially oval orifice having a perimeter materially less than the perimeter of the entering tube to reduce the tube and bring the same into contact with said bar at spaced peripheral points without imposing tube-shaping pressure of the interior surface of the tube against said bar, whereby said bar braces the tube against collapse upon emergence from the orifice, and passing said tube and bar through a circular orifice to free said tube from said bar and restore said tube to substantially circular shape.
